(57) **CLAIM**

We claim, the ornamental design for a metal detector search coil, as shown and described.

DESCRIPTION

FIG. 1 is a top view drawing of a metal detector search coil according to an embodiment of the design.

FIG. 2 is a right side view drawing of a metal detector search coil according to an embodiment of the design.

FIG. 3 is a bottom view drawing of a metal detector search coil according to an embodiment of the design.

FIG. 4 is an upper-right-rear perspective view drawing of a metal detector search coil according to an embodiment of the design.

FIG. 5 is a front view drawing of a metal detector search coil according to an embodiment of the design.

FIG. 6 is an upper-right-front perspective view drawing of a metal detector search coil according to an embodiment of the design.

FIG. 7 is a lower-right-rear perspective view drawing of a metal detector search coil according to an embodiment of the design.

FIG. 8 is a rear view drawing of a metal detector search coil according to an embodiment of the design; and,

FIG. 9 is a lower-right-front perspective view drawing of a metal detector search coil according to an embodiment of the design.
